DESIGN FOR A LAMP STAND

Simon Matzner, New York, N. Y.

Application November 19, 1945, Serial No. 123,897

Term of patent 3½ years

(Cl. D48—20)

To all whom it may concern:

Be it known that I, Simon Matzner, a citizen of the United States, residing in New York city, county of New York and State of New York, have invented a new, original, and ornamental Design for a Lamp Stand, of which the following is a specification, reference being had to the accompanying drawing, forming part thereof.

In the drawing:

The dominant features of my design reside in the portions shown in full lines.

The ornamental design for a lamp stand, as shown and described.

SIMON MATZNER.
